MEANS FOR CONTROLLING THE SPEED OF TRAINS.

1,293,779.

Specification of Letters Patent. Patented Feb. 11, 1919.

Application filed February 19, 1915. Serial No. 9,433.

To all whom it may concern:

Be it known that we, LAWRENCE WELSEY HORNE and WARREN NOBLE CRANE, citizens of the United States, and residents of, respectively, county of Bergen, town of Woodridge, State of New Jersey, and county of Bergen, town of Ridgefield Park, and State of New Jersey, have invented certain new and useful Improvements in Means for Controlling the Speed of Trains, of which the following is a specification.

This invention is a further advance in an art that has been developed by ourselves and others through the medium of a series of 15 steps more or less closely associated.

In this application certain portions will be found that have been previously used in a very similar manner but whereas in the past we have principally confined ourselves to devices working through magnetic attraction and direct current electromagnets, in this invention alternating current is used, and in lieu of electromagnetic attraction we obtain our control and the operation of the 20 parts by transformed currents varying according to the operative conditions of the transformers and particularly by their relation one to the other.

We do not however desire it understood 25 that we change the positions of the transformers but we do change surrounding conditions in a manner and for a reason that will be fully set forth as the specification progresses.

The following is what I consider the best means of carrying out this invention and,

The accompanying drawings form a part of this specification in which—

Figure 1 shows in elevation, partly in plan 40 our complete device.

Fig. 2 shows in section a portion of a rail and indicates the relative position of the transformer coil.

Fig. 3 shows a diagram of the arrangement of our device in relation to a track.

Similar reference numerals indicate like parts in all the figures where they appear.

Our device operates in conjunction with the train line air pipe and the primary object of the invention is to lower the pressure and apply the brakes by discharging the air from the train line air pipe under predetermined conditions or at a time when it is desirable to do so.

A train line air pipe is indicated at 1, and 55 at 2 we show a short exhaust nipple which may discharge into the atmosphere. Arranged between these two members is an electromagnetically operated valve indicated at 3 and having suitable electrical connection 60 by means of which the operation of the valve is controlled. Another electrically operated valve is shown at 4, and is by the means of the pipe 5 and reducing valve 6 connected to a suitable source of air supply such as the 65 reservoir.

From this second valve 4 a pipe 8 leads to a timing cylinder 7 through a speed regulating valve 9 and a piston 10 operated in one direction by a spring 11 is adapted to be 70 forced downward by air entering through the pipe 8 and speed controlling valve 9, the rapidity of the movement of the piston 10 being determined by the quantity of air passing through the port of the valve 9.

At 12 we show an alternating current generator capable of delivering to other portions of our device a sufficient electric current.

At 13 we indicate a section of rail which may be of ordinary shape, weight and 80 strength but we desire that this particular section of rail should be what is termed manganese or non-magnetic rail.

Thus far we have indicated what might be termed purely mechanical devices and 85 now so that the separate parts and their operation may be fully understood we will detail the peculiar requirements that we expect to fulfil including as we progress the particular portions of our mechanism upon 90 which we will depend to accomplish the desirable results.

We arrange an alternating current generator 12 and we prefer to provide an independent means for driving the generator 12.

Arranged low down on the locomotive and adjacent to the running rail is a transformer which consists of a primary 14, and parallel secondaries 15 and 16. It will be noted that this transformer is of an open core type and 100 by its arrangement in close proximity to a running rail it will be appreciated that an ordinary steel rail will act as the armature or core bridge of the transformer.

The primary 14 of the transformer is connected across the leads from the generator 12 so that the primary 14 will be energized 105 at all times during the operation of the gen-

- erator 12. It will also be noted that the valves 3 and 4 are energized from the generator 12, but that the circuits through the valves are retained by means of a relay 17, 5 which is in turn energized from the secondaries 15 and 16. It will be understood that under normal conditions and when the transformer 14, 15 and 16 is passing over an ordinary steel rail, the current induced in 10 the secondaries 15 and 16 because of the presence of the steel rail and the resultant shortening of the air gap in the magnetic field, will retain the armature of the relay 17 elevated closing the circuit between the 15 contact 18 and the terminal 19. Now, however should the transformer pass over a non-magnetic section of rail the absence of a magnetic path between the primary and secondaries of the transformer will lower the 20 voltage of the current induced in the secondaries 15 and 16 to such an extent that the relay 17 energized thereby will find itself unable to retain the armature in a position to close the contact 18 with the terminal 19. 25 The opening of this circuit will interrupt the sustaining circuit through the valve 4 with the result that this valve will open and air will be admitted through the reservoir pipe 5, the reducing valve 6, the pipe 8, 30 velocity controlling device 9 into the timing cylinder 7 depressing the piston 10 and interrupting the circuits 20 and 21 through the disk 22. By the time the piston 10 has moved to an extent sufficient to displace the 35 disk 22, the transformer will have reached a magnetic section of rail and the circuit through the relay 17 will be closed, but the circuit through the contacts 25—26 being broken by the movement of the valve 4 this 40 valve will remain open until the circuit therethrough is closed by the disk 22 reaching the contacts 23 and 24 which reestablish the circuit through the valve 4 closing the valve. The piston 10 may then return to its 45 normal condition. Its return interrupts the circuit through the contacts 23 and 24, but the interruption having no effect as the circuit through the valve 4 is maintained through its own disk 27 which has, by the 50 closing of the circuit through 23 and 24, been caused to close the circuit through the contacts 25 and 26.
- Let us consider that a non-magnetic section 55 has caused an interruption of the current through the valve 4 and that air entering the pipe 8 is forcing the piston downward, thus causing disk 22 to interrupt circuit to the valve 3. Disk 22 will gradually return after it has established the circuit to valve 4. 60 The complete downward and return movement of the disk 22 consumes a definite time and should the transformer reach and pass over a second non-magnetic rail before this timing operation has been completed the circuit through the valve 3 will be open and

the release of the air from this valve will so lower the pressure of the train line air pipe that the brakes will be applied.

The first interruption will open the circuit of the relay between 18 and 19 thus operating the valve 4 and opening the circuit between 20 and 21 as well as the circuit between 25 and 26. The opening of the circuit between 20 and 21 is however, delayed until the piston 10 has moved a predetermined distance downward at which time the piston rod will engage and move the disk 22. An operation which we desire to delay. The re-establishing of the circuit between 18 and 19 will not return the parts to their original condition, as we have provided that an element of time shall elapse before the parts are returned to their inoperative position. The element of time is determined by the rate of travel of the piston 10, the speed of which is controlled by the quantity of air which is allowed to enter the cylinder 7 through the valve 9; a second interruption occurring within the specified time after the first, the circuit through the valve 3 will be open and the brakes will be applied.

We desire that the operation of our device shall be definitely controlled and that operation shall only occur when conditions make them desirable. From the diagram shown in Fig. 3 it will appear that control sections consist of a plurality of non-magnetic sections arranged in pairs. The first non-magnetic section is indicated at A the second at B, at the first section we may get 100 an interruption through the valve 4 without effective result if sufficient time is consumed in traveling between points A and B for the piston 10 to fully return or if the section B is under the control that we will 105 soon describe. The space between C and D is shorter than that between A and B and the space between E and F is still shorter than that between C and D. As the time between any two non-magnetic points is determined by the piston 10, the closer non-magnetic sections are to each other the slower must be the speed to avoid an effective automatic operation.

We avoid an operation of the valve 3 at 115 the sections B, A and F when such is desirable by placing adjacent to each of these sections a laminated core 30 upon which is arranged a plurality of parallel coils 31, 32, 33 and 34, the leads of which terminate 120 in common conductors 35 and 36. A track relay 37 operated from a signal battery closes the circuit between the conductors 35 and 36, or opens it as desired.

The wire used in the coils 31, 32, 33 and 125 34 is a heavy stranded wire, and when the ends of the coils are disconnected, or the circuit therethrough opened by the relay 37, the only path for the transformer current is the path of possible leakage through the 130

air gap, but when the leads from the coils are connected or short-circuited by the relay 37, an efficient path between the coils of the transformer is provided. This path for the 5 transformer current probably results from the fact that when the coils are closed or short-circuited, the primary of the transformer induces a current of high amperage and low voltage in the closed track coils, 10 and these coils, in turn, induce a current of low amperage and high voltage in the secondaries of the transformer. In other words, the track coils serve as additional transformer coils, so arranged as to shorten 15 the air gap between the primary and the secondary of the transformer making the induction of current in the secondaries of the transformer more readily possible when the track coils or the leads therefrom are 20 closed.

For some time past it has been customary to use manganese frogs and cross-overs in railway track and these members would cause an operation of our device, unless we 25 adopted means for preventing an operation for sustaining our device during its passage over these frogs or cross-over sections. To accomplish this we provide that there shall be a manganese rail 44 in the track directly 30 opposite the frog and if a cross-over is used manganese sections will usually be found in both sides of the track. In Fig. 1 we show a transformer 40 which will be carried adjacent to the opposite or left hand rail 13. 35 This transformer will be connected in parallel with the coils, 14, 15 and 16. When the transformer which we have numbered 40 is passing over an ordinary steel rail, the rail will offer such a ready path for the primary 40 circuit that the effectiveness of the secondary will be lowered to a very great extent. When however the transformer 40 is passing over a non-magnetic or manganese section 45 the path for the induced circuit from the primary is holding through the secondary and will produce therein a current sufficient to sustain the relay 17 so that the circuit through 18 and 19 will not be interrupted.

The arrangement that we have described 50 insures that the two transformers shown shall not operate at the same time except at the control sections where an operation is desired. Normally when the transformer shown at 14, 15 and 16 is in operation, transformer shown at 40 is choked, and when the transformer shown at 40 is in operative 55 condition, the transformer shown at 14, 15 and 16 will be found to have its efficiency lowered by the absence of a track magnet 60 or a magnetic rail.

When the operation of the speed control apparatus is desired at the manganese control sections it will be seen that the transformer 40 is choked due to the presence of 65 magnetic metal in the left hand rail, and

the efficiency of the transformer 14, 15 and 16 is lowered due to the presence of manganese or non-magnetic metal in the right hand rail.

Having carefully and fully described our 70 invention what we claim and desire to secure by Letters Patent is:

1. Means for controlling the speed of trains comprising a plurality of valves, a transformer the secondary of which is 75 adapted to control the operation of said valves, a source of current supply for the primary of said transformer, a rail adjacent to said transformer and having diamagnetic sections adapted to interrupt the 80 current induced in the secondary of said transformer to operate said valves and means for retaining said valves inoperative during the passage of said transformer over diamagnetic sections. 85

2. A device of the character described comprising a plurality of valves and a transformer, means for supplying current to said valves and to said transformer, means controlled by said transformer for controlling 90 the operation of said valves, a track having diamagnetic sections for varying the current flow through said transformer to thereby control the controlling means for 95 said valves.

3. A device of the character described, having in combination a plurality of valves and a primary and secondary current supply, means operated by said secondary current for operating one of said valves and a 100 timing cylinder, a piston operable therein controlled by said valve and circuit controlling means operated by said piston and adapted to control the operation of the other valve as and for the purpose set forth. 105

4. A device of the character described comprising the combination of a plurality of valves, a timing device adapted to control one of said valves and a transformer for controlling the operation of both said valves, 110 an armature for said transformer adapted for a relative motion in relation to said transformer having non-magnetic sections and an induction device having a magnetic core and winding and arranged adjacent to 115 said non-magnetic sections and adapted to have the circuit therethrough opened or closed to influence the operation of said transformer and to thereby control the operation of said valves as and for the purpose 120 set forth.

5. Means for controlling the speed of trains comprising a plurality of controlling means and means for controlling them, said controlling means including a plurality of 125 transformers, a diamagnetic rail approximate to one said transformer for choking said transformer to obtain an effective operation thereof, and a diamagnetic rail interrupting the path of induction through said 130

second transformer to obtain an effective operation thereof.

6. A device of the character described having a plurality of electrically controlled devices, a plurality of transformers in a circuit and controlling said devices, a track having magnetic and diamagnetic section and adjacent to one said transformer to induce and interrupt an induced current through said transformer and a track having magnetic and diamagnetic sections choking the

flow of current through the other transformer and alternately allowing a clear flow of current through said transformer.

Signed at New York city, in the county 15 of New York and State of New York this 30th day of January 1915.

LAWRENCE W. HORNE.
